**RECIPROCATING PUMP PISTON AND
ROD CONNECTION**
Arthur L. Leman, P.O. Box 24068, Houston, Tex.
Filed Oct. 3, 1963, Ser. No. 313,575
13 Claims. (Cl. 92—243)

This invention relates to reciprocating pumps, and particularly double acting pumps used for circulation of drilling fluid or "slush" in oil well drilling operations, wherein alternating opposite pressures of substantial value are experienced. The invention is concerned more particularly with the improvement of drilling pumps of the type in which the piston and rod assembly is by a tapered threaded connection adapted for quick, easy removal and replacement of the piston without disturbing the operative installation of the pump rod in the pump cylinder.

The invention aims to provide for the demountable piston and rod assemblies such as here concerned an improved construction and arrangement whereby the pump piston and rod connection is stressed and stabilized to prevent unwanted working loose of the piston from the rod in service.

In the operation of oil well drilling pumps the presence of abrasive matter or slush in the pump fluid inevitably causes wear limiting the working life of and requiring the occasional replacement of the piston. This necessity for replacement of the pump piston resulted in the development of a pump piston and rod connection, as shown in the Leman Patent 2,741,518, wherein the construction and arrangement of the piston and rod connection was made such that the piston could be changed without removing the rod from the pump. This quickly demountable form or type of pump assembly was accomplished, as shown in my mentioned prior patent, by means of a threaded tapered connection of the piston to the rod.

However, operating experience showed that this joining or securing of the piston to the rod only through a tapered threaded length had the disadvantage of working loose in service. That is, undue wear and slippage of the threaded surfaces was experienced with the mentioned prior construction, which was thereby shown to lack sufficient axial rigidity to withstand the extreme slush pump service conditions, involving the rapid reciprocation of the piston, and subjection of it to high fluid pressures on the order of 3000 lbs p.s.i. and more for some of the deep wells.

This invention improves upon the construction of my above mentioned prior patent by the provision of a pump rod and piston connection in which those parts are engaged at conformant, inner and outer threaded and plain taper formations, whereby the assembly is afforded the desired axial rigidity to withstand the extreme pressure and abrasive wear conditions of reciprocating slush pump service. The novel pump rod and piston connection hereof is further characterized in that the threaded and plain tapers of the piston are predeterminedly smaller than the threaded and plain tapers of the rod, whereby when the assembly is made up it has greatly increased resistance to the forces tending to induce rocking of the parts and the wearing thereby of the threads, these being the forces which have heretofore caused a loosening of the assembly and ultimately the backing off of the piston from the rod.

Another feature of the invention is that, whereas in the prior Leman patent construction above referred to the bore of the piston core was required to be sealed, by an end cap which served to trap foreign matter passing the threads of the connection, the piston may more cheaply and easily be formed hereunder with a central axial passage cut all the way through the piston core, in that the

2

provision and prestressed engagement of the plain piston and rod tapers of the invention serves adequately to seal as well as to afford axial or stabilizing rigidity to the connection.

5 My invention will be fully understood from the following specification taken together with the accompanying drawings, in which:

FIG. 1 is a partly sectioned side view of a preferred embodiment of my invention wherein the piston and rod connection is fully assembled or made up;

FIG. 2 shows the connection similarly as in FIG. 1 but with the piston and rod in an intermediate state of assembly; and

15 FIG. 3 shows the FIG. 1 piston and rod connection with the parts in an initial stage of assembly.

20 In the drawings the piston rod of a double acting reciprocating slush pump is indicated at 5, and is shown further to have an outer terminal portion 6 formed into three sections. The larger or inner section of the terminal portion is formed as a threaded taper or tapered section 7, and is of a length for good purchase by, or more particularly for secure threaded engagement with, a corresponding or mating piston portion as hereinafter explained. Threads of varying taper and pitch may be 25 employed on this threaded taper section 7, which may have for example, a $\frac{3}{16}$ in. per foot on diameter taper and 8 pitch threads as in the embodiment illustrated.

25 The piston rod terminal portion 6 is provided outwardly of threaded taper 7 with an intermediate section 30 formed as a relatively straight or substantially cylindrical length 8, said intermediate straight section or length terminating outwardly in a right angular reduction or flat end face 9, and said flat end face 9 defining with said generally cylindrical length 8 an intermediate external shoulder, or shoulder section, of said terminal rod portion.

35 The terminal rod portion 6 is formed outwardly of said intermediate shoulder as a plain taper or tapered section 10, which outer section 10 tapers down from end face 9 and is of appreciable longitudinal extent, whereby to form 40 a sufficient or suitable piston supporting or bearing surface as later mentioned.

45 The plain tapered section 10 may be formed with various tapers similarly as the threaded tapered section 7, including preferably a slightly larger or steeper taper than that of threaded tapered section 7, the plain tapered section herein having, by way of example, a $\frac{1}{2}$ " per foot on diameter taper, as compared with the aforementioned $\frac{3}{16}$ " taper of the threaded tapered section.

50 Concentrically received on the terminal portion 6 of the pump rod 5 is a piston having a core 11 formed with a central transversely extending portion to which is intimately bonded a circumferential rubber packing comprising the oppositely projecting, radially flexing portions or lips 12, 13, the said lips defining with the medial core portion a generally cylindrical surface for sliding contact with the cylindrical wall or liner of the pump during reciprocating action of the rod and piston.

55 The piston core 11 further has an axial passage cut centrally there through and with portions variously formed for threaded and sliding engagement on counterpart sections of the rod terminal portion 6, as hereinafter detailed.

60 A cylindrical inner flange or hub 14 is integrally projected at one or the inner side of the piston core 11, and 65 extends substantially to underlie the inner packing 12. The core passage is formed with a threaded taper 15 at said inner hub 14, the taper 15 extending in the illustrated embodiment to about the mid-point of the core 11 for the desired substantial threaded engagement and bearing support of the piston, and more particularly the inner side thereof, on the rod.

At the other or outer side of core 11 is integrally projected a flange or hub 16 balancing the opposite hub 14 and extending similarly as that does to underlie the corresponding outer packing 13. The core passage is formed within the hub 16 with an intermediate plain or smooth portion 17 extending from the threaded taper 15 to a transverse end face or wall 18 about midway or more of the length of hub 16. This intermediate core passage portion 17 gradually tapers from the diameter of the roots of the threads 15 towards the diameter of the cylindrical rod portion 8, and reduces to a minor cylindrical length 17a fitting closely around that mating rod surface 8. The right angular inset of the core passage at end face 18 will be understood to define with intermediate passage portion 17a an internal shoulder faced oppositely to and proportioned to abut or oppose the mating external shoulder 8, 9 of rod 5.

In accordance with the invention, the piston core 11 further has a cylindrical sleeve 19 integrally projected beyond hub 16 and also the packing 13, and which is formed at the core passage with a plain taper 20 generally conformant to the plain taper 10 of rod 5, whereby the sleeve 19 provides bearing support for the piston on the rod 5 at the outer side of core 11. Sleeve 19-20 is seen also as formed with a number of longitudinal recesses 21 for rotative engagement by a tool or wrench such as conventional and therefore not shown, whereby upon engagement and manipulation of the tool the piston may be quickly and easily backed off the rod while that remains in normal use position in the pump cylinder.

Further in accordance with the invention, the threaded and plain tapers 15, 20 of the piston are deliberately made smaller than the mating tapers 7, 10 of the rod, whereby when the connection is fully made up the piston and more particularly its inner hub 14 and outer sleeve 19 are stressed in circumferential tension. In addition, the relative extent and proportioning of the parts is so arranged under the invention that as the piston is advanced over the end of the rod the threaded tapers 7, 15 are rotated together a number of turns before the plain tapers 10, 20 are initially engaged, and the plain tapers are in turn initially engaged at a point in the relative closing of the rod and piston before the shoulders 9, 18 are brought into engagement.

It should be pointed out that the intermediate step or shoulder formations 9, 18 while desirable and convenient for gaging purposes, are not necessary to the invention construction. Thus the plain tapers 10, 20 may alternatively be formed as an extension of substantially the same conical surface as the threaded tapers 7, 15, and the threaded and plain taper engagement may alternatively be delineated or differentiated merely by an intervening recess in or enlargement of the piston core passage.

In the preferred embodiment of the invention which is herein shown and described, the gaging is such that the corresponding tapers 7, 15 of the rod and the piston are threaded together about three turns before the conformant plain tapers 10, 20 of the rod and the piston are brought into positive metal-to-metal contact, and the making up of the assembly proceeds through about one more turn, or a fourth relative rotation of the threaded piston and rod tapers 7, 15, before the assembly becomes completely made up under compressive stress through continued advance of the parts into compressively stressed positive contact engagement.

In the making up of the invention assembly or connection, then, the piston is slid onto the rod and rotated by hand, with the threads of the inner tapers 7, 15 in full circumferential engagement, through the necessary number of turns. This will first bring the plain tapers 10, 20 into engagement. The available further rotation of the parts will be understood to subject both piston extremities to circumferential stress, as already explained and also to stress the piston in longitudinal tension. This longitudinal tension will be seen to be produced by the

stressing of the plain piston taper 20 at a faster rate than the threaded piston taper 10. Thus in the present embodiment and with the tapers as above mentioned the advance of the threads through four turns will produce about .008 in. interference, and the relative closing of the plain tapers the longitudinal distance of one turn of the threads will produce about .005 in. interference on said plain tapers. It will be seen, then, that the gaging or proportioning of the rod and piston under the invention is such as to produce, by the closing to metal-to-metal positive surface engagement of the parts, both a circumferential and a longitudinal stressing of the piston whereby the piston threads 15 are tensioned on the rod threads 7 both radially and axially of the assembly. In this way the piston and rod connection is afforded the needed axial rigidity, stabilizing the piston on the rod and preventing relative movement of the parts such as heretofore producing wear and loosening of the threads.

It will be appreciated also that the conformant tight-fitting engagement of the plain tapers 10, 20 of the rod and piston adequately seals the connection against escape of fluid or foreign matter past the threads 7, 15 eliminating any need for an end cap or closure means such as would tend to weaken the piston core and render it more costly to make.

It has been demonstrated by actual use of the connection on a slush pump assembly employing a piston of 6½ in. size and subject to working pressures above 3000 lbs. per square inch, that the invention solves the stated problem in the manner herein described.

My invention is not limited to the particular embodiments thereof illustrated and described herein, and I set forth its scope in my following claims:

I claim:

1. A double acting reciprocating pump piston and rod assembly comprising a piston rod having an outer terminal portion; an inner threaded tapered section formed on said terminal portion; and outer plain tapered section formed on said terminal portion; a piston comprising a transversely extending metallic core; an axial passage formed through said core whereby it is receivable on said terminal portion of said rod; an inner hub extension integrally projected at one side of said core and formed at said passage with a threaded taper for conformant fit on said threaded tapered section of said rod; and an outer hub extension integrally projected at the other side of said core and balancing said inner hub extension, said outer hub extension formed at said core passage with a plain taper for conformant fit on said plain tapered section of said rod; and said threaded and plain tapers of said piston hub extensions being predeterminedly smaller than said threaded and plain tapered sections of said terminal rod portion, whereby when said piston is advanced over said rod to operative position said threaded and plain piston hub tapers are prestressed in circumferential tension, and said pump piston and rod assembly is afforded axial rigidity to prevent said threaded piston hub taper from working loose from said threaded tapered rod section.

2. A double acting reciprocating pump piston and rod assembly according to claim 1 wherein the longitudinal spacing and relative proportions of the tapered rod sections and piston hub tapers is such that the inner threaded tapered pair is threaded together three turns when the outer plain tapered pair makes contact.

3. A double acting reciprocating pump piston and rod assembly according to claim 1 wherein the threaded taper is about $\frac{1}{16}$ in. per foot on diameter, and the plain taper is about $\frac{1}{2}$ in. per foot on diameter, whereby when the piston and rod are fully made up there is about .005 in. interference in the plain taper and about .008 in. interference in the threaded taper.

4. A double acting reciprocating pump rod and piston assembly comprising a cylindrical pump rod having a piston receiving portion, an inner threaded taper formed

on said portion, an outer plain taper formed on said rod portion, an annular piston comprising a transversely extending metallic core, a central bore formed axially through said core for reception of said piston on said rod, a threaded taper formed in a length of said bore extending to one side of said core and for conformant fit on said threaded tapered rod section, a plain taper formed in a length of said bore extending to the other side of said core, said plain taper of said bore adapted for conformant fit on said plain tapered section of said rod, 10 said threaded and plain tapers of said rod and piston being constructed and arranged such that when said assembly is made up the threaded tapers are turned a number of times before the plain tapers are engaged, and such that the plain tapers are engaged before the assembly is fully made up, said threaded and plain tapers of said piston core being predeterminedly smaller respectively than the threaded and plain tapers of said rod portion whereby upon said fully making up of said assembly said threaded and plain tapers of said piston core or prestressed in circumferential tension.

5. A double acting reciprocating pump piston and rod assembly according to claim 4 wherein the threaded tapers are made up three turns when the plain tapers are brought into contact.

6. A double acting reciprocating pump piston and rod assembly according to claim 4 wherein the plain tapers make contact about one turn of the threaded tapers before the assembly is fully made up.

7. A double acting reciprocating pump piston and rod assembly according to claim 4 wherein said core has at said plain taper a longitudinal extent presenting thereon a non-round formation for engagement by a tool for backing said piston off said rod.

8. In a double acting reciprocating pump piston and rod assembly as defined in claim 4, a shoulder formed on said pump rod portion adjacent said threaded taper, a shoulder formed on said piston bore adjacent its said threaded taper, said rod and piston shoulders oppositely faced and abutively engaged when said assembly is fully made up.

9. A double acting reciprocating pump rod and piston assembly comprising a piston rod having an outer terminal portion, and on said portion an inner threaded taper and an outer plain taper; and a piston received on said rod and comprising a core having a central radially extending body adapted to mount packing means, said core having inner and outer hub extensions and a sleeve formation integrally projected beyond the outer of said hub extensions, 45 said core further having a central axial through passage,

said passage formed at said inner hub with a threaded taper for threaded engagement on said threaded rod taper, and formed at said sleeve formation with a plain taper for conformant fit on said plain rod taper.

5 10. A double acting reciprocating pump piston and rod assembly according to claim 9, wherein said threaded and plain piston tapers are predeterminedly smaller than said threaded and plain rod tapers, whereby when the assembly is made up the threaded and plain piston tapers are stressed in circumferential and also longitudinal tension such that the assembly is afforded greatly increased axial rigidity and resistance to loosening of the threaded engagement of the piston on the rod subject to the pressures on and reciprocating action of the pump.

11. A double acting reciprocating pump rod and piston assembly comprising a cylindrical piston having longitudinally opposite sections and a central bore extending continuously through both sections, said bore at one section being tapered and circumferentially threaded and at 20 the other section being plain tapered, said assembly further comprising a piston rod having adjacent the free end a longitudinally tapered and circumferentially threaded portion with threading conformant to that of said first piston section, said rod also having in similar 25 longitudinal spacing from said threaded portion a non-threaded plain portion tapered in such relation to that of said other piston section as to form therewith a fluid seal upon making up of the assembly into operative status.

30 12. A double acting reciprocating pump rod and piston assembly according to claim 11 wherein one said section of the piston bore is of smaller diameter than the corresponding portion of the piston rod received therein.

13. A double acting reciprocating pump rod and piston assembly according to claim 11 wherein both said sections of the piston bore are smaller in diameter than the corresponding portions of the piston rod received therein and whereby on full making up of the assembly both said piston sections are prestressed in circumferential 40 tension.
